United States Patent Office

Des. 183,806
Patented Oct. 28, 1958

183,806

COVERED CASSEROLE

Jens H. Quistgaard, Copenhagen, Denmark, assignor to Dansk Designs Inc., Great Neck, N. Y.

Application May 19, 1958, Serial No. 50,956

Term of patent 14 years

(Cl. D44—1)

FIG. 1

FIG. 2

Fig. 1 is a plan view of the covered casserole, showing my new design; and

Fig. 2 is a side elevation thereof.

I claim:

The ornamental design for a covered casserole, substantially as shown.
